UNITED STATES PATENT OFFICE.

NOAH M. COYNER, OF FRANKFORT, OHIO.

CLOTHES-RACK.

SPECIFICATION forming part of Letters Patent No. 777,185, dated December 13, 1904.

Application filed January 20, 1904. Serial No. 189,814. (No model.)

To all whom it may concern:

Be it known that I, NOAH M. COYNER, a citizen of the United States, residing at Frankfort, in the county of Ross and State of Ohio, 5 have made certain new and useful Improvements in Clothes-Racks, of which the following is a specification.

My invention is an improvement in that class of clothes-racks having a series of hinged 10 or pivoted arms adapted to be extended horizontally and radially or folded in vertical position parallel to each other when not required for use. I have combined a series of such hinged arms with a box adapted to contain 15 them when not in use, the swinging cover or door of said box being adapted to support the arms horizontally in position for use.

The invention is embodied in the construction, arrangement, and combination of parts 20 hereinafter described, and shown in the accompanying drawings, in which—

Figure 1 is a perspective view of my improved clothes-rack, the hinged arms being folded within the box and the door or cover 25 thereof secured in closed position. Fig. 2 is a vertical section showing the hinged arms extended in horizontal position, as in use. Fig. 3 is a horizontal section on the line 3 3 of Fig. 2. Fig. 4 is a face view of the upper 30 portion of the apparatus, the hinged arms being shown folded within the box and the door of the latter open. Fig. 5 is a perspective view of the hinged holder to which the arms are pivoted.

A indicates the box to which the arms B are permanently attached by means of a hinged holder C. The box A is rectangular and oblong and provided with a hinged door a, which constitutes its front side and is provided with a top shelf or bracket a'. The door may be secured in closed position by a catch a" or any other suitable device. The holder C is constructed of sheet or plate metal whose parallel members are separated by the 45 thickness of the arms B and provided with loops c to receive the hinge bolt or pivot c'. (See Fig. 2.) The arms B are pivoted between the plates and adapted to swing into radial position, as indicated in Figs. 2 and 3, 50 or to be folded parallel, as shown in Fig. 4,

whereby they are adapted to be inclosed in the box A. The holder C swings upon the hinge c', which is held in a metal piece or bracket c", secured to the upper portion of the box, as indicated in Figs. 2 and 3. A 55 spiral spring D surrounds the hinge-pivot c', and its ends are so arranged in connection with the metal piece c" and the holder C of the arms B as to tend to throw the arms out of the box and up to the horizontal position 60 indicated in Fig. 2. When in such position, the swinging door a of the box is closed, and its bracket or shelf a' then affords a support for the arms, as will be readily understood. As shown, the said shelf or bracket a' is located a short distance below the top a" or far enough to provide a slot or side opening 65 through which the holder C may project when the arms are extended, as shown in Fig. 2. The arms B are then swung laterally from 70 each other or separated radially, as indicated in Fig. 3. When no longer required for use, they are swung back into parallel position, and the door a being opened they are pressed back into the box, as indicated in Fig. 4, 75 and the door a then closed and secured, as in Fig. 1. I thus provide a simply-constructed, durable, compact, and easily-portable clothes-rack which may be hung up wherever desired 80 for use and which protects the hinged arms 85 from dust when the same are folded. It is also adapted to be easily manipulated for placing the arms in working position or housing them when not in use.

The box A is adapted to be hung upon a nail against the wall or upon any other fixed support, or it may be attached to the latter in any preferred manner.

Having thus described my invention, what I claim as new, and desire to secure by Letters 90 Patent, is—

1. The improved clothes-rack comprising an oblong box, a series of arms and a holder in which they are secured, said holder being hinged to the top portion of the box within 95 the same, and a swinging door, which closes the entire front portion of the box, save at the top where the arms are adapted to project when in use, the top portion of said door being adapted to support the arms horizontally 100

when the door is closed in the manner described.

2. The improved clothes-rack, comprising an oblong box, a series of arms and a holder in which they are pivoted, said holder being hinged to the top portion of the box, a coil-spring applied to the hinge of the said holder, and tending to throw the arms upward, and a swinging door adapted to form the front portion of the box and to hold the arms within

the same when folded laterally and vertically, substantially as described.

In testimony whereof I have signed my name to this specification in the presence of two subscribing witnesses.

NOAH M. COYNER.

In presence of—

D. L. SUTHERLAND,
W. R. BEARD.
